UNITED STATES PATENT OFFICE.

GEORGE I. ROCKWOOD, OF WORCESTER, MASSACHUSETTS.

APPARATUS FOR MAINTAINING THE WATER-LINE IN STEAM-BOILERS.

SPECIFICATION forming part of Letters Patent No. 770,314, dated September 20, 1904.

Application filed November 18, 1901. Serial No. 82,619. (No model.)

To all whom it may concern:

Be it known that I, GEORGE I. Rockwood, a citizen of the United States, residing at Worcester, in the county of Worcester and 5 Commonwealth of Massachusetts, have invented a new and useful Improvement in Apparatus for Maintaining the Water-Line in Steam-Boilers, of which the following is a specification accompanied by drawings, forming 10 part of the same, in which—

Figure 1 represents an apparatus for maintaining the water-line in a steam-boiler embodying my invention and shown in central vertical sectional view. Fig. 2 is a plan view of 15 the steam-trap forming part of my apparatus and shown in sectional view on line 22, Fig. 1.

Similar reference-letters refer to similar parts in the different views.

The object of my present invention is to provide 20 an apparatus for maintaining the water-line in steam-boilers, by which the boiler can be maintained substantially full of water, thereby obviating the necessity of maintaining a large steam-space in the top of the boiler, 25 the water being automatically maintained at a maximum level in the boiler and upon the level of the steam-pipe leading therefrom with means for separating the overflow-water from the steam, whereby the steam is delivered dry 30 to the engine, and I accomplish these results by means of the apparatus hereinafter described, and set forth in the annexed claims.

Referring to the accompanying drawings, A denotes a boiler, which may be of any usual 35 or known type of construction. In the present instance it consists of an ordinary upright tubular boiler having vertical flues or pipes A' and provided with a burner B or other suitable means by which heat is applied to 40 the water in the boiler. As near the top of the boiler A as practicable I introduce a pipe C, leading, preferably, from its side to an auxiliary chamber, within which the pipe C, by means of an elbow C', is extended downward 45 nearly to the bottom of the chamber, forming a steam-separator C², the lower end C³ of the pipe being open. The pipe C lies in a horizontal plane and enters the boiler just above the desired water-line and near the top of the 50 boiler, so that steam generated in the boiler

will pass freely through the pipe C, and as the water rises above the desired water-line the overflow-water will also pass simultaneously with the steam through the pipe C into an auxiliary and separate steam-chamber D, 55 from which the steam product of the boiler is taken through a steam-pipe E. The sides C⁴ of the pipe opposite the side wall of the chamber are cut away, so that the depending pipe or separator C² is open on one side and 60 at its lower end. From the top of the auxiliary chamber D is a steam-pipe E, leading to the engine. The boiler A near its bottom is connected with a water reservoir or tank G by a feed-pipe F, provided with check-valves 65 F', F², and F³. Between the check-valves F' and F², I place a force-pump of any known and suitable form of construction, in the present instance consisting of a reciprocating plunger-pump H, driven by a crank-wheel H', by which 70 water from the tank G is forced into the boiler A and against the steam-pressure therein and maintained at the level of the steam-pipe C. Leading from the bottom of the auxiliary chamber D is a pipe I, by which the auxiliary 75 chamber D is connected with the interior of a steam-trap J, which communicates at its bottom through a pipe K with the feed-pipe F between the check-valves F² and F³. The opening in the bottom of the trap J is closed by a 80 valve L, connected to a lever M, which is pivoted at one end to a bracket N and carries at the opposite end a hollow float O. The check-valves F', F², and F³ are of the usual form of 85 construction and are capable of opening to allow water to flow from the tank G to the boiler A, but close to prevent its return.

Water is fed to the boiler A by means of the pump H until it reaches the level of the pipe C, substantially filling the boiler A. The 90 steam formed in the boiler A passes through the pipe C into the auxiliary chamber D, any water passing through the pipe C with the steam being carried downward by its own gravity through the separator C² to the bottom of the chamber D, while the steam is delivered through the open side C⁴ of the pipe into the chamber D in a dry state to be taken through the pipe E to the engine. Wherever 95 an excess of water occurs in the chamber D, 100

due to water being carried over by the steam and accumulating therein or due to an overflow of water occasioned by the excessive feeding by the pump H, it will flow through 5 the pipe I into the steam-trap J and accumulate therein until the float O is raised, thereby opening the valve L and causing the steam-trap J to communicate through the pipe K with the feed-pipe F behind the check-valve 10 F³. Whenever an open communication is thus established between the top of the boiler and the feed-water pipe F behind the check-valve F³ the check-valve F³ will become closed by the steam-pressure in the boiler, and the 15 pump H will then force the water which has accumulated in the trap J into the boiler, and the overflow from the boiler will be returned to the boiler by the pump. When the water in the steam-trap J has been carried into the 20 boiler, the float O will fall by gravity and close the valve L, thereby removing the steam-pressure from behind the check-valve F³, allowing water to be taken from the reservoir G through the pipe F and fed into the boiler 25 by the pump H. The automatic action of opening and closing the valve L by the presence or absence of water in the steam-trap J sufficient to lift the float O will thereby control the water-supply to the boiler from the 30 reservoir G and cause the water-line to be maintained substantially at the lower edge of the pipe C.

My apparatus is especially intended to be used in connection with boilers for motor-vehicles in which the boiler-space is restricted and the variation between high and low water mark is limited.

My present invention enables me to carry the boiler substantially full of water instead of 40 devoting a considerable portion of the boiler-space to the storage of steam. I employ an auxiliary chamber for steam storage, and by means of my improved separating device I am enabled to separate the water from the steam 45 and deliver the water in a dry state to the engine. I also utilize the water accumulating in the auxiliary chamber D for the purpose of feeding the boiler, and I also automatically maintain the water-line at the level of the 50 steam-pipe C leading from the boiler by employing a feeding mechanism capable of feeding water to the boiler slightly in excess of the requirement for making steam and providing means for automatically returning the 55 overflow back to the boiler.

As the operation of my apparatus contemplates an overflow of water with the steam into the auxiliary chamber, it becomes necessary to provide for a separation of the water 60 and steam before the latter is taken to the engine, and any known device can be employed for this purpose.

My apparatus comprises the following elements: first, a boiler with a steam-pipe leading 65 therefrom at or near the top of the boiler,

an auxiliary chamber for the steam, a separating device by which the water carried into the steam-chamber from the boiler is separated from the steam in order to deliver dry steam to the engine, and a communication between 70 the bottom of the steam-chamber and the feed-water pipe, said communication being a gravity-actuated trap as determined by the overflow of water from the steam-chamber.

What I claim as my invention, and desire to 75 secure by Letters Patent, is—

1. In an apparatus for maintaining the water-line in steam-boilers, the combination of the following instrumentalities, a steam-boiler, a separate steam-chamber, a pipe connecting said steam-chamber with said boiler at its water-line, means for feeding water to said boiler from a source of water-supply and comprising a pump and a check-valve between said pump and the source of water-supply, a 80 steam-pipe leading from said steam-chamber, a drip-pipe leading from said steam-chamber to the feed-water pipe between the pump and said check-valve, a gravity-actuated trap by which the passage through said drip-pipe is 85 controlled, and a float in said trap whereby the flow of water from said steam-chamber will operate to open said drip-pipe, substantially as described.

2. The combination with a steam-boiler, of 95 a separate steam chamber or separator, a pipe leading from said separate steam-chamber to the engine, means for feeding water to said boiler, a pipe connecting said steam-chamber to said boiler, whereby the steam and overflow-water are simultaneously conducted to 100 said steam-chamber, and means whereby the overflow and condensed water is automatically returned to the boiler from said steam-chamber, substantially as described.

3. The combination with a steam-boiler, of 105 means for feeding water to said boiler from a source of water-supply, a separate steam-chamber, a horizontal overflow-pipe connecting said steam-chamber with said boiler at its top, whereby said boiler is maintained substantially full of water, a drip-pipe leading from said steam-chamber to remove the overflow-water therefrom and a steam-trap whereby the passage through said drip-pipe is 110 controlled, substantially as described.

4. The combination of a boiler, means for feeding water to said boiler from a source of water-supply, an overflow-pipe at or near the top of said boiler and leading to a separate 115 steam-chamber, a steam-pipe leading from said steam-chamber, a drip-pipe leading from said chamber, means for automatically returning the drip-water from said steam-chamber to the boiler and comprising a steam-trap and means for automatically opening and closing the passage through said drip-pipe as determined by the water in said trap, substantially 120 as described.

5. The combination of a boiler, means for 125

feeding water to said boiler from a source of water-supply, an overflow-pipe leading from said boiler at or near its top to a separate steam-chamber, a steam-pipe leading from said steam-chamber, a steam-separator in said steam-chamber, a drip-pipe leading from said steam-chamber, and a steam-trap for automatically returning the drip-water from said

steam-chamber to the boiler as controlled by the water in said trap, substantially as described.
